Des. no. 20,115

UNITED STATES PATENT OFFICE.

JAMES D. FOSTER, OF IRONTON, OHIO, ASSIGNOR TO THE FOSTER STOVE COMPANY, OF SAME PLACE.

DESIGN FOR A COOKING-STOVE.

SPECIFICATION forming part of Design No. 20,115, dated August 26, 1890.

Application filed July 21, 1890. Serial No. 359,441. Term of patent 7 years.

To all whom it may concern:

Be it known that I, JAMES D. FOSTER, a citizen of the United States, residing at Ironton, in the county of Lawrence and State of Ohio, 5 have invented and produced a new and original Design for Stoves; and I do declare the following to be a full, clear, and exact description of the same, reference being had to the accompanying photographs, forming a part 10 thereof.

The accompanying illustration gives a perspective view of my design, which is intended especially for square or rectangular stoves.

Referring particularly to the illustration, 15 it will be noticed that the leading feature of my design consists of a curved line or arc A in the lower portion of the panel of each door and a series of diverging straight lines B, extending from said arc or curved line, the 20 straight lines being raised from the body of the panel and the curved line being cut in the same. The surface between the straight lines is roughened, although this is not an essential feature. This portion of my design 25 is placed on the oven-door C, the reservoir-door D, and the warming-oven door E; but the reservoir or the warming-oven, or both, may be omitted, if desired.

The doors of the warming-oven and the reservoir are identical in design, and are provided around their edges with the borders F, consisting of an outer scroll or vine G and an inner wider portion G', which is composed of coiled stems H, encircling flowers or rosettes 35 I and terminating in the leaves J. The stems are so arranged that at the ends of the panel they bring the flowers to the corners of the same, while the leaves meet at the center of the panel, and on the upper and lower sides 40 of the panel the stems are coiled in an S shape and encircle a flower at each of their ends.

The oven-door is considerably larger than the panel, and in each rear corner and in the space in front of the panel I form the scroll 45 or figure K. The smaller rear figures are adaptations of the figure composing the border G, and have in addition the offshoot L, consisting of an irregular body M and the plume N, projecting therefrom. The front figure 50 consists, primarily, of a stem O, bent into the form of a reversed S, and having a branch

P running from its lower extremity. Leaves P' project from this stem at various points of its length, and loops Q, inclosing dots R, are also formed thereon at different points. The 55 upper end of the stem is carried around so as to form nearly a complete circle, and is divided into a series of short stems and leaves. A line of bulbs or dots of various diameters S leads rearward from the upper end of the 60 stem over the corner of the panel. Around the edge of the panel I form a border T, which is composed of a vine or scroll of the same character as the border G.

The door U of the fire-box has a panel V, 65 within which I form a number of irregularly-diverging lines W, having enlarged upper ends to represent blades of grass, and around this panel I form a border X of the coiled stems and flowers or rosettes before described. 70

Below the door U is a rosette Y, the outer edge of which is circular, and in the center of which I arrange a single small circle Z. In the space between the two circles I provide the scrolls a and the ellipses b. 75

Having thus fully described my invention, what I claim, and desire to secure by Letters Patent, is—

1. The design for a cooking-stove, as herein shown and described. 80

2. In a design for a cooking-stove, the panel having the arc or curved line in its lower portion, the diverging lines radiating from the arc or curved line, and the flower and leaf work ornamentation, as herein shown and 85 described.

3. In a design for a cooking-stove, the oven-door having around its edge a border consisting of a running vine and a center panel, as herein shown and described. 90

4. In a design for cooking-stoves, the panel having a number of irregularly-curved lines, and a border ornamentation comprising scroll-work and rosettes, as herein shown and described. 95

In testimony whereof I affix my signature in presence of two witnesses.

JAMES D. FOSTER.

Witnesses:

JAMES ALEXANDER,
WILL H. FOSTER.
